(57) **CLAIM**

The ornamental design for a package for a medical device, as shown and described.

DESCRIPTION

FIG. 1 is a front perspective view of an embodiment of a package for a medical device showing our new design.

FIG. 2 is a rear perspective view of the package for a medical device of FIG. 1.

FIG. 3 is a right view of the package for a medical device thereof;

FIG. 4 is a front view of the package for a medical device thereof;

FIG. 5 is a left view of the package for a medical device thereof;

FIG. 6 is a rear view of the package for a medical device thereof;

FIG. 7 is a top view of the package for a medical device of FIG. 1.

FIG. 8 is a bottom view of the package for a medical device of FIG. 1.

FIG. 9 is an enlarged perspective view of the top front portion of the package for a medical device of FIG. 1, with the dash-dot-dot-dash broken lines surrounding the enlarged portion forming no part of the claimed design; and,

FIG. 10 is another enlarged perspective view of the top front portion of the package for a medical device of FIG. 1, with the dash-dot-dot-dash broken lines surrounding the enlarged portion forming no part of the claimed design.

The dash-dot lines in the Figures show portions of the package for a medical device which form no part of the claimed design.

The shade lines in the Figures show contour and not surface ornamentation.

1 Claim, 7 Drawing Sheets
